US00D955179S

(12) **United States Design Patent** (10) **Patent No.:** **US D955,179 S**
(45) **Date of Patent:** **** Jun. 21, 2022**

(54) **LUNCH BOX**

(71) Applicant: **MON BENTO**, Clermont Ferrand (FR)

(72) Inventor: **Annouk Voisin**, Clermont Ferrand (FR)

(73) Assignee: **MON BENTO**, Clermont Ferrand (FR)

(**) Term: **15 Years**

(21) Appl. No.: **35/510,535**

(22) Filed: **Sep. 17, 2020**

(80) **Hague Agreement Data**

Int. Filing Date: **Sep. 17, 2020**

Int. Reg. No.: **DM/210503**

Int. Reg. Date: **Sep. 17, 2020**

Int. Reg. Pub. Date: **Oct. 9, 2020**

(30) **Foreign Application Priority Data**

Mar. 20, 2020 (EM) 007763248-0001

(51) LOC (13) Cl. **07-07**

(52) U.S. Cl.

USPC **D7/602**; D7/629; D7/709

(58) **Field of Classification Search**

USPC D7/538, 554.1, 550.1, 555, 557, 601,
D7/629, 630, 709; D9/759, 761;
D3/276, 283, 284, 295, 302

CPC A45C 11/20
